UNITED STATES PATENT OFFICE.

LUSTER STILES, JR., OF BRANDENBURG, KENTUCKY, ASSIGNOR OF ONE-HALF TO JOHN HENRY CAIN, SR., OF BRANDENBURG, KENTUCKY.

FUEL VAPORIZER AND BURNER.

1,195,867.

Specification of Letters Patent. Patented Aug. 22, 1916.

Application filed March 10, 1915. Serial No. 13,431.

To all whom it may concern:

Be it known that I, LUSTER STILES, Jr., a citizen of the United States, residing at Brandenburg, in the county of Meade and State of Kentucky, have invented certain new and useful Improvements in Fuel Vaporizers and Burners, of which the following is a specification.

This invention relates to that type of 10 gaseous fuel burners, especially adapted for use as the heating element in ordinary cook stoves and ranges and more particularly relates to a kerosene burner in which the heating flame is rendered smokeless, together 15 with a particular valve mechanism for conjunctive use with such kerosene burner.

As a principal object, this invention contemplates the provision of a gaseous fuel burner and vapor fuel generator which may 20 be depended upon to automatically prepare the fuel before the combustion thereof in such manner as to obviate the nuisance and waste attendant upon a smoky heating flame.

25 It is a coördinate object to provide a self-indicating valve whereby the number of burners to be ignited may be regulated in any manner desirable with the character of the cooking being carried on.

30 An object more specific than the foregoing is to provide in a burner of the character set forth a substantially unburnable wick primarily saturated with the originally liquid fuel which may be ignited to institute 35 a vaporizing heat upon adjacent feeding portions of the burner until a continuance of the fuel flow results in the provision for the burner of a gaseous fuel, the heat from the combustion of which provides not only 40 for the usual cooking purposes but also as a generating heat to permit the continuance of such gaseous flow.

The above and additional objects which 45 will become apparent as this explanatory description proceeds, are accomplished by such means as are illustrated in the accompanying drawings, described in the following specification and then more particularly pointed out in the claims which are appended hereto and form a part of this application.

With reference to the drawings, wherein 55 there is illustrated the preferred embodiment of this invention as it is reduced to practice, and throughout the several views

of which like characters of reference designate similar parts: Figure 1 is a plan view of the burner as positioned within a stove of a customary make, parts being shown in section, Fig. 2 is an elevational view of the stove fitted with the burner of this invention and showing the operation of the indicating portion of the valve, Figs. 3 and 4 are sectional views taken upon the transverse plane indicated by the respective lines 3—3 and 4—4 of Fig. 1, looking in the directions respectively indicated by the arrows of such lines, Fig. 5 is a longitudinal section through the burner pipe showing the feed and the valve controlled burner orifices for such pipe, and Fig. 6 is a perspective view of the valve removed from its seat.

Referring now to the drawings, and more particularly to Fig. 1, in which the device is most clearly illustrated as a whole the numeral 10 indicates the front and side portions of a cook stove in which a burner such as is comprehended by this invention is to be desirably positioned. Such a burner includes a plurality of longitudinally parallel pipes, one of which as denoted by the numeral 11 connects as indicated at 12 with an inlet pipe 13 for the fuel and is superimposed above the vertically aligned burner pipe 14 with which it is connected by means of the laterally disposed pipes 15 and 16 respectively connected by means of suitable elbow joints in the manner indicated at 17 with the burner pipe 14 and the pipe 11, 90 while at the same time joined with each other at their opposite extremities by means of the transverse piping 18.

The foregoing sets forth the general assemblage of the particular form of burner and gaseous vapor generator of this invention which may be more particularly described as follows: Split supporting sleeves 19 are maintained by fastening means 20 upon the extremities of the vaporizing pipe 11 and carry the deflector plate 21 extending below such pipe. The pipe 15 is positioned below this deflector and to one side thereof while the pipe 16 is similarly positioned slightly above the said deflector in order that flames from the burner pipe 14 may strike the former in preference to the latter. The burner pipe 14 as particularly illustrated in Fig. 4 has mounted thereon the coating U-shaped supporting clamps 23 and is con-

nected by the already discussed means 17 to the pipe 15 in order to receive the heated vapor therefrom. Rotatably positioned within this pipe is the tapered cylindrical valve 24 which is provided with a plurality of elongated openings 25 desirably arranged as illustrated in Fig. 6 so that portions of all of said apertures may be alined longitudinally with respect to the valve while each of the central apertures extends laterally from such alinement on one side and the extreme apertures extend laterally therefrom in the opposite direction. One of these central apertures is also elongated as indicated at 26 beyond its counterpart all for the purpose to be hereinafter more fully set forth. Each of these valve apertures is adapted to register with escape or burner openings 25^a formed in the pipe 14 in which the cylindrical valve is snugly seated as before stated. This pipe 14 has one extremity threaded as indicated at 27 to engage with the connection 17 of the pipe 15 in the manner shown at 28 and rotation of the conical valve 24 is controlled by a stem 29 extending through the opposite end. This stem 29 projects through the wall 10 of the stove and carries outwardly thereof the handle 30 for movement with which there is also mounted upon the stem the indicating finger 31 of an L-shaped formation as illustrated in Fig. 1, permitting the finger to rotate in a vertical plane closely parallel to the stove front 10, as the stem is revolved. The portion of the stove front adjacent this finger 31 carries a semicircular scoring provided with indicator marks 32, the vertically central one of which indicates that the full number of burner apertures 25^a are in use while the adjacent marks to either side of said vertically central one mean respectively, when the indicator 31 is pointed thereat, that the two end burners or the two side burners, as may be the case, are in use. It is also possible to adjust the valve 24 through its handle so that the elongated portion 26 will register with one burner opening although no other aperture portion will so register, thus assuring the use of a single burner.

Secured to the U-shaped supporting clamps 23 and similarly half encircling the pipe 14 on the opposite side are the substantially double L-shaped support 33, the extremities of which are paralleled in the same horizontal plane in order to rest upon the bottom of a tray 34 and suspend the same from said pipe 14 which tray 34 is adapted to be lined with asbestos or some other wicking material 35, preferably of a non-inflammable character. Oil passing as a liquid in its original state through the inlet connections 13, vaporizing pipe 11, through the coil presented by the connecting pipes 16 and 15 successively is conducted to the burner pipe 14 where the valve handle 30

may be so manipulated as to establish communication between the valve apertures 25 and the burner openings 25^a permitting the oil, still in its liquid state to escape exteriorly of the burner pipe and to drip therefrom upon the asbestos or other wicking 35 in the tray 34 supported immediately below such burner pipe, until the said wick is saturated. An ignition of this wick when so saturated with the liquid oil will result in the action of the flames of such ignition upon the pipe 15, the deflector 21 serving to direct flames to this pipe 15 which flames otherwise would not reach the same, and accordingly serves to shorten the time required to bring sufficient heat to the coils 15-16, through which the liquid oil is flowing on its way to its point of consumption in the burner pipe. Moreover the deflector 21 transmits the heat of this primary ignition directly to the vaporizing chamber of the pipe 11 in which the oil is first heated to its point of vaporization before being led into the coils 15-16 where it is maintained at a high temperature or is heated if so found desirable. The vapor upon leaving the burner pipe 24 escapes through the openings 25^a in a manner directed by manipulation of the inner cylindrical valve and of course is ignited by the flame of the primary ignition in the tray 34, which latter being no longer fed by additional amounts of the liquid fuel from the burner gradually dies down after its purpose has been accomplished the heat from the vapor flames acting in a precisely similar manner upon the deflector 21 to maintain both the pipes 11 and 15 at their proper temperature. If all four (4) burners are to be lighted, portions of each of the elongated apertures 25 are alined longitudinally of the cylindrical valve so as to successively register with the small burner openings 25^a, the indicator 31 occupying the position illustrated in Fig. 2. Turning the handle 30 to either the right or the left until the indicator 31 contacts with either of the points marked 2 on the handle scale of Fig. 2 will throw out either the end apertures or the central apertures as may be desired, depending upon whether a mild diffuse heat or a similarly mild but comparatively concentrated heat is wished by the operator. If but a single burner is to be placed for operation, the valve is turned so that none of the apertures 25 register with their respective burner openings, save the especially elongated portion 26. In every case control of the valve is facilitated by the tapered formation thereof which enables the operator to first loosen the valve in its seat by drawing outwardly upon the handle previous to rotating the valve to the desired position, thus obviating the ordinary wear and tear upon the valve member due to the frictional contact with its seat and in no

wise interfering with the proper positioning of the valve in any of the manners above set forth.

It will be understood that the pipes 11, 15, 5 16 and 14, may be connected with a stationary portion of the stove frame by a conventional form of bracket, not shown, or any other suitable means.

From the foregoing it will be clearly apparent that means have been accomplished whereby the objects previously presented are capable of being attained so that this invention may therefore be claimed as possessing the advantages and desirability set forth in such objects.

What is claimed is:—

1. In a fuel vaporizing burner, an inlet for liquid fuel, a burner pipe for both liquid and vapor fuel, parallel longitudinal pipes connected with one another at one end, means for connecting the remaining end of one of said pipes with said inlet, connections between the corresponding end of the remaining pipe of said parallel pipes 25 and the burner pipe, said burner pipe having burner openings formed therein, a rotary valve within said burner pipe and having openings adapted to register at times with the said burner openings, means for controlling said valve, means for indicating the position of said valve, and a burner tray suspended from said burner pipe.

2. In a fuel vaporizing burner, an inlet for liquid fuel, an upper pipe connected 35 with said inlet, a parallel pipe connected with the first-mentioned pipe and in a plane slightly below the latter, a third parallel pipe connected with the second-mentioned pipe and in a plane below the latter, said second and third pipes being positioned to opposite sides of the first-mentioned pipe, a flame deflector secured beneath said first-mentioned pipe, a burner pipe directly beneath said deflector and connected with the 45 third parallel pipe, said burner pipe having burner openings formed in its upper face, means for controlling the discharge of fuel from said burner openings, and a burner tray positioned beneath said burner pipe.

3. In a fuel vaporizing burner, a main pipe, a fuel supply pipe connected with one end of said main pipe, connected side pipes parallel with the said main pipe, one of said side pipes being connected with said main pipe, said side pipes and said main pipe being in different planes, a lower burner pipe connected with one of said side pipes, said lower burner pipe being provided with burner openings in its upper face, a tapering valve member within said burner pipe and adapted to open one or more of said burner openings, means for controlling said valve member, means for indicating the position of said valve member, a lined burner 65 tray beneath said burner pipe, connections

between said tray and said burner pipe, a deflector, and means for securing said deflector beneath said main pipe.

4. In a fuel vaporizing burner, a plurality of longitudinal parallel pipes, means for connecting the corresponding ends of a pair of said pipes, means for connecting the opposite end of one of said pair with the corresponding end of the remaining pipe, a fuel inlet pipe connected with the opposite end 70 of said remaining pipe, a burner pipe below said remaining pipe, means for connecting the opposite end of the other pipe of said pair with said burner pipe, said burner pipe having burner openings, a valve member having elongated transverse openings formed therein and offset with respect to one another to connect with one or more of said burner openings, means for controlling said valve member, an indicating 80 member mounted upon said means, a burner tray beneath said burner pipe, and means for deflecting flames from said burner and directing the same toward the pair of parallel pipes to vaporize the fuel passing 90 through the same.

5. In a fuel vaporizing burner, a fuel inlet pipe, an upper pipe connected by its forward end to said liquid fuel inlet pipe, a side pipe connected by its rear end to the 95 rear end of said upper pipe, an opposite side pipe, means for connecting the forward ends of said side pipes, a lower burner pipe beneath said upper pipe, means for connecting the rear end of said lower burner pipe with 100 the rear end of the second-mentioned side pipe, said lower burner pipe having burner openings formed therein, means for controlling the escape of fuel from said burner openings, a burner pan beneath said lower 105 burner pipe, and a deflector carried by said upper pipe.

6. In a fuel vaporizing burner, a plurality of parallel longitudinal pipes connected to one another in regular order, one of said 110 pipes serving as the lower burner pipe and provided with burner openings, a sleeve rotatably mounted in the lower burner pipe and provided with transverse elongated offset openings for registration with the respective burner openings whereby the desired number of burner openings may be employed by rotary adjustment of said sleeve, means for indicating the position of said sleeve, a deflector carried by the uppermost of said pipes, and a burner pan supported beneath said lower burner pipe. 115

7. In a fuel vaporizing burner, a plurality of connected pipes, one of said pipes serving as the burner pipe and having burner openings formed therein, a hollow rotary member positioned in said burner pipe and provided with an elongated transverse opening for each burner opening, said elongated transverse openings being offset from one 125 130

another, means for rotating said rotary member to adjust said transverse elongated openings with respect to said burner openings, and means to indicate the position of 5 said rotary member.

8. In a fuel vaporizing burner, a burner pipe provided with a row of burner openings, means for supplying fuel to said burner pipe, a rotary hollow member positioned in said burner pipe and having trans- 10 verse elongated openings for registration

with said burner openings, a projecting stem for said rotary member, means mounted upon said stem for rotating said rotary member, and means for indicating the position of said rotary member. 15

In testimony whereof I affix my signature in presence of two witnesses.
